**FORWARD AND REVERSE PAPER FEED MEANS
IN SELECTIVE PRINTING MACHINES**
Morton P. Matthew, Norwalk, Conn., assignor to The
Bunker-Ramo Corporation, a corporation of Delaware
Filed Dec. 4, 1963, Ser. No. 328,037
11 Claims. (Cl. 101—94)

The present invention relates to a printer and more particularly to an improved paper feed mechanism for successively feeding a sheet to be printed toward and away from a printing station and advancing the sheet a distance of one printed line at the end of each printing cycle.

While the improved paper feed and gainer mechanism of the present invention may have other applications, it is particularly adapted for and shown applied to a printer of the type illustrated and described in an application for United States Letters Patent of Richard H. Podoloff et al. Serial No. 153,627, filed November 20, 1961, and entitled Printer for Data Processing Apparatus, now U.S. Patent No. 3,146,701. The printer illustrated and described in said application comprises a continuous paper web looped around a pivotally mounted cylindrical platen for movement toward type elements at a printing station to print on the web. It is necessary, therefore, to move the paper from an observation station where the printing can be observed to a printing station under the platen where printing occurs; and then return the web from the printing station back to the observation station after a printing operation. In addition, the paper web must be advanced one line of printing after each printing operation.

The mechanism illustrated and described in said patent application for controlling the paper feed utilizes gear and ratchet wheels on the platen and a reciprocating rack and pawl. The rack lies on the gear wheel and when the rack is reciprocated the gear wheel and platen are rotated in alternate directions to move the paper web. Adjacent the end of the forward stroke of the rack, the pawl engages the ratchet wheel and lifts the rack from engagement with the gear wheel but continues to rotate the platen during its forward movement. However, during the rearward stroke neither the rack nor ratchet moves the platen until the rack is again lowered into engagement with the gear wheel. Thus, the paper feed advances the paper web a distance greater than it is withdrawn and the difference is made equal to the distance of one line of printing to provide a gain in the paper feeding mechanism. While the paper feed and gainer mechanism described and claimed in the Podoloff et al. application works quite satisfactorily in performing its intended function, it constitutes a complicated mechanical arrangement having a substantial number of parts; and the parts are not positively connected to insure reliable operation of all operation conditions.

One of the objects of the present invention is to provide an improved paper feed and gainer mechanism which positively controls the movement of the paper web by pulling the opposite ends of the loop of paper extending around a freely rotatable platen.

Another object is to provide an improved paper feed and gainer mechanism for a printer which converts the movement of an oscillating driving element having the same angular movement in opposite directions to oscillate a driven element and take-up reel through different degrees of angular movement in opposite directions.

Still another object of the present invention is to provide an improved paper feed and gainer mechanism for a printer which is of relatively simple and compact construction, economical to manufacture and one which is

2

reliable in operation to positively reciprocate the paper web to and from a printing station as well as advance the web through a distance of one printed line after each printing operation.

These and other objects will become more apparent from the following description and drawings in which like reference characters denote like parts throughout the several views. It is to be expressly understood, however, that the drawings are for the purpose of illustration only and are not a definition of the limits of the invention, reference being had for this purpose to the appended claims.

In the drawings:

FIGURE 1 is a side elevational view of a printer shown partly in section to illustrate the relationship of the parts of the paper feed and gainer mechanism prior to a printing operation;

FIGURE 2 is a schematic view illustrating the paper web and driving means therefor and showing the relationship of the parts when the paper web has been moved to a printing position;

FIGURE 3 is an extended perspective view of the parts of the gainer mechanism for driving the take-up reel and showing the concentrically mounted pair of one-way clutches operated by an eccentrically mounted oscillating swing-plate;

FIGURE 4 is a front view of the paper feed and gainer mechanism;

FIGURE 5 is a side view of the one-way clutch for controlling the movement of the take-up reel counterclockwise;

FIGURE 6 is a view similar to FIGURE 5 showing the other one-way clutch for driving the take-up reel clockwise;

FIGURE 7 is a side view of the swing-plate and shaft for the take-up reel and showing the unequal angular movement of the shaft and take-up reel when driven from the eccentrically mounted swing-plate;

FIGURE 8 is a perspective view of the spring operated paper gripping and releasing mechanism for moving the paper from the observation station to the printing station and showing how the paper is gripped between the pivoted bails; and

FIGURE 9 is a side elevational view of the spring actuated paper gripping and releasing mechanism and showing one of the bails engaging a stop to rock the bails relative to each other to release the paper.

As stated above, the paper feed and gainer mechanism of the present invention is shown applied to a printer of the type illustrated and described in the application for United States Letters Patent of Richard H. Podoloff et al. Serial No. 153,627 for purposes of illustration. Suffice it to state herein that the printer illustrated is particularly adapted for use in banks to print the same digital information on a bank book (not shown) and a record tape T_p . The bank book is mounted on a sliding carriage 10 for movement to a printing station where it overlies an anvil 11 at the end of a pivoted frame 12 constituting a press. Record tape T_p is looped around a cylindrical platen 13 at the printing station and the platen is mounted on a pivoted frame 14 and constitutes a press. Positioned between the anvil 11 and platen 13 are a plurality of type bars 15 arranged in side by side relationship and movable relative to each other. Each type bar 15 has the same type faces 16 and 16a at the top and bottom edges corresponding to the characters to be printed such as, for example, the numerals 1 to 9 and 0. Each type bar 15 is moved to an adjusted position relative to the other bars by a spur gear 17 for meshing engagement with rack teeth 19 on the type bar and each spur gear 17 is mounted on a pivoted frame 18. The

spur gears 17 are normally engaged with the rack teeth 19 on the respective type bars 15 and the plurality of spur gears are rotated to adjust the type bars and position the desired type faces 16 and 16a at the printing station. A control mechanism, including an electromagnet for each frame 18, rocks its frame to disengage its spur gear 17 from the rack teeth 19 of its bar when the desired type face is at the printing station.

After the type bars 15 have been adjusted relative to each other the pivotal frame 12 mounting the anvil 11 is rocked toward the print bars to print the information on, for example, a bank book at the printing station; and the platen 13 is rocked toward the opposite side of the print bars to print the same information on the record tape T_p .

The driving mechanism for the printer comprises an electric motor 22 which operates through a belt 23 and counter-shafts 24 and 25 to drive a selection shaft 26 connected to drive the spur gears 17 for adjusting the type bars 15 and a print shaft 27 for printing on the bank book and record tape, respectively. The selection shaft 26 and print shaft 27 are operated alternately in succession so that the type bars 15 will be first adjusted relative to each other and after which a printing operation takes place. The driving mechanism also includes a shaft 28 for performing other functions in the printer. The pivoted frame 12 mounting the anvil 11 is rocked toward the type bars 15 by a cam 29 on the print shaft 27 which operates through a cam follower 30 on a link 31 interposed between the cam 29 and frame. Selecting mechanism 34 on the shaft 28 controls the link 31 to position it between the print shaft 27 and frame 12 or withdraw it therefrom to control printing on the bank book. The pivoted frame 14 mounting the platen 13 has links 33 depending therefrom which are operated by eccentrics 32 on the print shaft for moving the platen and record tape T_p toward the type bars 15 to print on the tape.

In accordance with the present invention an improved paper feed and gainer mechanism 35 is provided for moving the record tape T_p from an observation station S1 at the top of platen 14 to a printing station S2 under the platen and then return the tape from the printing station to the observation station. During the return of the tape from the printing to the observation stations the paper feed and gainer mechanism 35 advances the tape a distance of one printed line.

In general, the record tape T_p is in the form of a continuous web with a loop of the web between a supply roll 36 and take-up reel 37, see FIGURES 1 and 2, extending forwardly over guide rolls 38 and 39, around the platen 13 and then over guide roll 40 as it leads to the take-up reel. The take-up reel 37 and a pivoted paper gripper 41 engage the web of record tape T_p at the opposite ends of the loop and pull it in opposite directions around the platen 13. The tape T_p is moved from the observation station S1 illustrated in FIGURE 1 to the printing station S2 illustrated in FIGURE 2, by the pivoted gripping device 41 which is rocked by a spring 42 to pull the end of the loop a distance equal to the distance from the observation station to the printing station a blank section of the tape adjacent the last printed line at the printing station. Such movement of the tape T_p is controlled by the driving means for the take-up reel 37 which permits it to rotate counterclockwise. The take-up reel 37 is positively driven clockwise to pull the web at the opposite end of the loop and move the newly printed line from the printing station S2 to the observation station S1. The positive drive of the take-up reel 37 acting through said web pulls on the pivoted gripping device 41 and rocks it against the action of spring 42 from the position illustrated in FIGURE 2 to that illustrated in FIGURE 1. Such rocking movement continues until a length of web T_p corresponding to the distance between the printing station S2 and observation station S1 has moved over the platen 13 after which the gripping

device 41 releases the web to permit an additional length of web to feed from the supply roll 36 into the loop. The last printed line on the record tape T_p is located at the observation station at the beginning of a printing operation and the first movement of the driving mechanism for adjusting the type bars 15 operates the take-up reel 37 from the position illustrated in FIGURE 1 to that illustrated in FIGURE 2. After a printing operation has been performed the take-up reel 37 is moved back to its initial position plus one printed line from that illustrated in FIGURE 2 to that illustrated in FIGURE 1.

Take-up reel 37 is driven by an oscillating swing plate 43 and the swing plate is oscillated by a link bar 44 pivotally connected thereto at one end and connected to a lever 45 at its opposite end. Lever 45 is mounted to rock on a pivot 46 and has a cam follower 47 engaging a cam 48 on the selection shaft 26. The opposite end of the lever 45 has a pin 49 projecting into a slot 50 in the lower end of the link bar 44. A spring 51 acts on the lever 45 to rock it clockwise as viewed in FIGURE 1 to hold the link bar 44 down and thereby rock the swing plate 43 to the position illustrated in FIGURE 1. Upon rotation of the selection shaft 26 to adjust the type bars 15, the lever 45 is rocked counterclockwise to release the link bar which is then actuated upwardly by the spring 52 to rock the swing plate to the position illustrated in FIGURE 2.

The gainer mechanism 35 converts the equal angular movement of the swing plate 43 in opposite directions to unequal angular movements of the take-up reel 37 in opposite directions. Referring now to FIGURES 3 and 4, the gainer mechanism is shown as comprising a shaft 56 having a hub 57 for locking engagement with one end of the take-up reel 37. Swing plate 43 is mounted to rock about an axis X on a cylindrical boss 58 projecting inwardly from the side plate 55 of the machine frame. Shaft 56 is journaled for rotation in side plate 55 of the frame for rotation about an axis Y eccentric to the axis X of the cylindrical boss 58 and oscillating swing plate 43. In the illustrated embodiment the axis X of plate 43 is located at the right hand side of the axis Y of the shaft 56 and take-up reel 37. It will be understood that the cylindrical boss 58 may be mounted on the frame of the machine for turning movement relative to the shaft 56 to vary the lateral eccentricity of the axes of the swing plate 43 and shaft 56.

Mounted on the shaft 56 are a pair of one-way clutches 59 and 60 having radial arms 61 and 62, respectively, as shown in FIGURES 3, 5 and 6. The one-way clutches 59 and 60 may be of any conventional form and in the illustrated embodiment each comprises a cylindrical hub 59a or 60a with tangential recesses 59b or 60b and spring loaded rollers 64 or 64a in the recesses for gripping engagement when turned in one direction and releasing the parts of the clutch when moved in the opposite direction. As shown in FIGURES 3 and 5 the clutch 59 acts as a brake to control the movement of the web T_p and has its inclined recesses 59b and rollers 64 arranged to grip the shaft 56 and clutch hub 59a when the latter rotate counterclockwise relative to arm 61 and release the shaft and hub 59a during clockwise movement relative to arm 61; and the one-way clutch 60 has its angular recesses 60b and rollers 64a arranged to grip and drive the shaft 56 upon clockwise movement and release the shaft during counterclockwise movement.

As shown most clearly in FIGURE 3 the swing plate 43 is of generally diamond shape having a crank pin 65 projecting from one side parallel to its axis X and pivotally connected to the upper end of the link bar 44. A pair of pins 66 and 67 project from the opposite side of the swing plate 43 adjacent its outer ends and the pins extend into slots 68 and 69 in the arms 61 and 62 of the one-way clutches 59 and 60, respectively. Thus, when the swing plate 43 is rocked counterclockwise, the motion is transmitted through the pin 66 and slot 68 in the arm 61 of

the one-way clutch 59 to rock the arm and permit the shaft 56 and take-up reel 37 to rotate counterclockwise. On the other hand, when the swing plate 43 is rocked clockwise the motion is transmitted through the pin 67 and slot 69 to positively rock the clutch 60, shaft 56 and take-up reel 37 clockwise.

Due to the eccentricity of the axes X and Y of the swing plate 43 and shaft 56, a counterclockwise movement of the swing plate through a given angle about its axis X will permit the shaft 56 to rotate through a given angle about its axis Y. Also the clockwise movement of swing plate 43 through the same given angle about its axis X will rotate the shaft 56 through a greater angle. This is illustrated graphically in FIGURE 7 where the eccentricity of the swing plate 43 and shaft 56 is indicated by the distance e . Lines drawn horizontally through the two axes X and Y and through the axis X of the cylindrical boss 58 and pins 66 and 67 will subtend angles C which are equal and opposite on opposite sides of the axis of the swing plate 43. A line from the axis Y of the shaft 56 through the pin 66 then subtends an angle B while a line from the axis Y through the pin 67 subtends an angle A. As will be clearly observed from FIGURE 7, the angle A is greater than the angle C and that the angle B is less than the angle C. Therefore the angle A must be greater than the angle B. Thus, when the swing plate 43 is oscillated in opposite directions through angles equal to the angle C the pin 66 will have moved through an angle B with respect to the axis Y of the shaft 56 while the pin 67 will have moved through a greater angle A with respect to the axis Y. By adjusting the eccentricity e , the shaft 56 and take-up reel 37 as shown in FIGURE 3 can be made to move through different angular distances and produce a different linear movement of the paper web T_p corresponding to a distance of one printed line. In other words, by mounting the swing plate 43 on an axis X eccentric to the axis Y of the shaft 56, the pin 67 moves through a given distance in an arc closer to the axis Y than does the pin 66 located further away from axis Y and therefore moves its one-way clutch 60 through a greater arc with respect to its axis Y than the pin 66 and its one-way clutch 59. The gainer mechanism thereby produces an unequal angular movement of the shaft 56 from the equal angular movement of the swing plate 43.

As the paper web T_p is wound on the take-up reel 37 the diameter of the paper roll increases so that the same angular movement of the take-up reel will produce different linear movement of the web. To compensate for this and maintain the gain or linear advance of the paper web T_p constant, an adjustable stop 72 is provided for limiting the angular movement of the oscillating swing plate 43. As will be observed by reference to FIGURES 1 and 3, the link bar 44 is moved downwardly by the driving mechanism including the lever 45 which limits the extent of clockwise movement of swing plate 43. Lever 45 releases the bar 44 at the beginning of a printing operation. The link bar 44 is then moved upwardly by the spring 52. This upward movement of the link bar 44 and oscillation of the swing plate 43 counterclockwise under the action of the spring 52 is limited by the engagement of the driving pin 66 with the adjustable stop 72. Stop 72, in turn, projects from one side of a sleeve 73 rotatable on a shaft 74 and the sleeve has an outwardly projecting feeler arm 75 which bears against and feels the increase in diameter of the take-up reel 37. Thus, as the take-up reel 37 increases in diameter, as viewed in FIGURE 3, the sleeve 73 and adjustable stop 72 are rocked clockwise to decrease the counterclockwise swinging movement of the swing plate 43. As the shaft 74 is offset with respect to the axis X of the swing plate 43 a different portion of the adjustable stop 72 will be engaged by the driving pin 66. In order to attain the same movement of the paper web T_p for different diameters, the surface edge 76 of the adjustable stop 72 is provided with the

proper curvature to produce the same linear advance of the web T_p at different diameters of the take-up reel 37.

The web gripping device 41 is shown in detail in FIGURES 8 and 9 as comprising a pair of pivotally connected bails 80 and 81. As shown in FIGURE 8, the supply roll 36 of the paper web T_p is mounted on a shaft 82 journaled in the side plates 55 of the frame. Bail 80 has a crossbar 83 and inwardly directed arms 84 at the ends of the crossbar so dimensioned that the bail encloses a portion of the supply reel 36. The arms 84 of the bail 80 are pivotally mounted in the side plates 55 of the frame by means of pins 85 projecting therethrough. Bail 81 has a crossbar 86 and right angular arms 87 of a width to straddle the arms 84 of the bail 80 and the arms 84 and 87 are pivotally connected to each other by means of pins 88. It will be noted by reference to FIGURE 8 that the crossbar 86 of the bail 81 is in alignment with and overlies one edge of the crossbar 83 of the bail 80. Springs 42 act between the pivot pins 88 and the sides 55 of the frame to rock the bails clockwise as a unit. The web of record tape T_p extends upwardly and rearwardly over the rectangular crossbar 83 of the bail 80 and then around the cylindrical crossbar 86 of the bail 81 to reverse its direction. The tension of the web on the crossbar 86 of bail 81 rocks it toward the crossbar 83 of bail 80 to grip the paper therebetween. Continued pulling of the web forwardly from the position illustrated in FIGURE 8 will rock the bails 80 and 81 forwardly as a unit against the action of the springs 42 as illustrated in FIGURE 1. This counterclockwise rocking movement of the gripping device 41 continues until the extended end of an arm 87 of the bail 81 engages a stop pin 89 projecting inwardly from the side plates 55 of the frame. Continued counterclockwise rocking movement of the gripping device 41 then causes the bails to rock relative to each other as the counterclockwise movement of the pivot pins 88 continues, and this relative movement opens the bails and releases the paper web. The arrangement is such that the gripping device 41 permits the advance of a length of the web T_p equal to the length of web paid off from the take-up reel 37 before the extension of the arm 86 engages the stop pins 89. The continued movement of the take-up reel 37 in a clockwise direction then causes a feeding of a length of web corresponding to one line of printing on the web from the supply roll 36 between the bails 80 and 81 of the gripping device 41 and into the loop. One form of the invention having now been described in detail the mode of operation is explained as follows.

At the beginning of a cycle of operation of the printer the parts are in the relative position illustrated in FIGURE 1. To initiate a printing operation a bank book is mounted on the carriage 10 and moved to a printing station underlying the type bars 15. Upon operation of a suitable control element the driving mechanism operates through the motor 22, belt 23 and countershafts 24 and 25 to rotate the selection shaft 26. Rotation of the selection shaft 26 adjusts the type bars 15 relative to each other to position the desired sequence of the type faces between the anvil 11 and platen 13. Simultaneously, the rotation of the selection shaft 26 operates through the cam 48 and lever 45 to release the link bar 44. Link bar 44 is then moved upwardly by the spring 52 to rock the swing plate 43 from the position illustrated in FIGURE 1 to that illustrated in FIGURE 2. Referring now to FIGURE 3, the counterclockwise movement of the swing plate 43 is transmitted through the pin 66 and one-way clutch 59 to permit the shaft 56 and take-up reel 37 to rotate counterclockwise to pay out a length of the printed web T_p equal to the distance from the observation station S1 to the printing station S2. The gripping device 41 which grips the web tape T_p adjacent the supply roll 36 is rocked clockwise by spring 42 from the position illustrated in FIGURE 1 to that illustrated in FIGURE 2 when the tape is released to draw the loop rearwardly and move an unprinted area of the tape adjacent the last

printed line to the printing station. This movement of the take-up reel 37 and web of the loop is controlled by the engagement of the drive pin 66 with the adjustable stop 72, see FIGURE 2.

The machine is now ready for a printing operation and a cam 29 on the print shaft 27 operates through the cam follower 30 and link 31 to rock the pivoted frame 14 clockwise and press the bank book between the anvil 11 and type bars 15. Eccentric 32 on the print shaft 27 also rocks the pivoted frame 12 mounting the platen 13 toward the type bars to print the information on the tape Tp.

After the completion of the printing operation the lever 45 is released and actuated by the spring 51 to rock it clockwise as viewed in FIGURE 1. Clockwise rocking movement of the lever 45 acts through its pin 49 to pull the link bar 44 downwardly and thereby rock the swing plate clockwise from the position illustrated in FIGURE 2 back to the position illustrated in FIGURE 1. Clockwise rocking movement of the swing plate 43 is transmitted through the pin 67, see FIGURE 3, and one-way clutch 60 to rock the shaft 56 and take-up reel 37 in a clockwise direction. Due to the eccentricity of the axis X of the swing plate 43 with respect to the axis Y of the shaft 56, the clockwise swinging movement of the swing plate 43 rocks the shaft 56 to wind up the web and move the printed lines from the printing station S2 to the observation station S1. In so doing, shaft 56 is rocked through a greater angular distance than it was moved by the one-way clutch 59 during the unwinding corresponding to one line of printing.

It will now be observed that the present invention provides an improved paper feed and gainer mechanism which positively controls the movement of a record tape as it moves from an observation station to a printing station and return by pulling its opposite ends. It will also be observed that the paper feed and gainer mechanism converts the equal angular movement of an oscillating driving element to unequal angular movements of a take-up reel in opposite directions to advance the web a distance equal to one line of printing after each printing operation. It will still further be observed that the present invention provides an improved paper feed and gainer mechanism which is of relatively simple and compact construction, economical to manufacture and one which is reliable in operation to positively drive the paper web in opposite directions.

While a single embodiment of the invention is herein illustrated and described, it will be understood that modifications may be made in the construction and arrangement of elements without departing from the spirit or scope of the invention. Therefore, without limitation in this respect, the invention is defined by the following claims.

I claim:

1. In a printer of the type having type elements with a type face for each character to be printed, means for adjusting the plurality of type elements relative to a printing station, a platen roll at the printing station, a web of paper looped around said platen roll, means for mounting the type elements and platen roll for relative movement to print an impression from the type elements onto the web and driving means for the type element adjusting means and for relatively moving the type elements and platen roll in timed relation, the combination with said elements of said printer of an improved paper feed and gainer mechanism comprising a take-up reel connected to one end of the loop of paper for positively moving it in one direction, a spring actuated take-up means connected to the other end of the loop of paper for moving it in the opposite direction, a drive shaft connected to the take-up reel, a pair of one-way clutches mounted on said shaft, one of said one-way clutches being mounted to grip and rotate the shaft when turned clockwise and release the shaft when turned counterclockwise, the other of said clutches

controlling and limiting the rotation of the shaft when turned counterclockwise, a member mounted to oscillate on an axis eccentric to the axis of said drive shaft, and said member having a sliding connection with the one-way clutches to oscillate the clutches whereby to turn said shaft and web of paper through a greater arc in one direction than it is moved in the other direction.

2. In a printer having a cylindrical platen, type elements having a type face for each character to be printed, a web of paper looped around the platen, driving mechanism for moving the paper web from an observation station to a printing station and then back to the observation station comprising a take-up reel, a shaft connected to drive the take-up reel, clutch means permitting controlled rotation of the take-up reel shaft in one direction and positively turning the shaft in the opposite direction, an oscillating element mounted to rock on an axis eccentric to the axis on the drive shaft and having sliding connections with the clutch means at opposite sides of the axis of the drive shaft whereby the eccentric oscillating element produces different increments of arcuate movement of the drive shaft in opposite directions to advance the web a distance of one line during each oscillation, and a yielding device connected to the paper web and permitting movement thereof in one direction by the take-up reel and moving the web of paper in the opposite direction.

3. A driving mechanism for controlling the oscillation of a shaft successively in opposite directions with an increment of gain in the angular movement in one direction comprising a pair of one-way clutches mounted on the shaft, one of said clutches controlling rotation of the shaft in one direction and the other clutch positively driving the shaft in the opposite direction, an oscillating element mounted to rock on an axis eccentric to the axis of the shaft at one side thereof, and means connecting the oscillating element and clutches comprising members projecting from one of the oscillating and clutch elements and radial shoulders on the other element engaged by the members to transmit arcuate movement from the oscillating element to the clutches while permitting relative movement radially to compensate for the eccentricity of the oscillating element whereby to produce a greater increment of arcuate movement of the shaft in one direction than in the other.

4. In a printer, a cylindrical platen roll, a web of paper looped around said platen roll, a take-up reel at one end of the loop of paper web, a supply reel at the opposite end of the loop of paper web, a shaft connected to drive the take-up reel, a pair of one-way clutches mounted on the shaft, each of said clutches having radially extending arms with slots therein, an oscillating swing plate mounted to rock on an axis eccentric to the axis of the drive shaft for the take-up reel and having radial arms, pins extending from the radial arms of the oscillating swing plate through the slots in the radial arms of the pair of one-way clutches, respectively, driving means for oscillating the swing plate in opposite directions through equal arcs and acting through the pins to rock the radially extending arms of the separate clutches through unequal arcs, a pivotally mounted gripper between the supply reel and platen for gripping the paper, and a spring connected to the gripper to permit it to rock against the action of the spring in one direction and to move the gripper and web of paper gripped thereto in the opposite direction.

5. In a printer in accordance with claim 4 in which power operated means is connected to turn the swing plate in one direction, a spring connected to turn the swing plate in the opposite direction, and a stop controlling the movement of the swing plate under the action of the spring to limit the turning movement of the take-up reel.

6. A printer in accordance with claim 5 in which the diameter of the reel increases as the paper web is wound thereon, and means operated by the increase in diameter of the reel for actuating the stop and thereby controlling the angular movement of the reel as its diameter increases

to maintain a substantially constant linear movement of the paper web in one direction.

7. A printer in accordance with claim 6 in which the stop is mounted on a shaft and extends radially in the path of one of the connecting pins projecting from the swing plate, and a feeler mechanism engaging the periphery of the take-up reel for rocking the shaft as the diameter of the reel increases.

8. A printer in accordance with claim 4 in which the swing plate has a crank pin projecting from the side opposite the connecting pins, a driving crank having a crank pin, a rod connecting the crank pins on the driving crank and swing plate, said rod having a slot therein through which the pin of the driving crank extends, a spring connected to move the rod in the opposite direction when released by the driving crank pin, and a stop controlling the movement of the swing plate under the action of the spring to limit the turning movement of the take-up-reel.

9. A printer in accordance with claim 8 in which the driving crank releases the rod at the beginning of a printing operation for operation by the spring, said gripper moving said paper web to a printing station, driving means for operating said driving crank at the end of a printing operation to positively actuate the connection rod, swing plate and take-up reel.

10. A printer in accordance with claim 4 in which the pivotally mounted gripper comprises a pair of bars pivotally connected to each other intermediate the ends thereof, one of said bars being pivotally mounted adjacent one end, gripping elements projecting from one side of the bars and cooperating to grip the paper web therebetween,

said pivotally connected bars rocking as a unit about the pivotal mounting of one of said bars, yielding means connected to at least one of said bars for biasing the bars in one direction, and a stop for engaging the other of said bars for rocking it relative to the pivoted bar to release the paper web.

11. A printer in accordance with claim 4 in which the pivotally mounted gripper comprises a first bail pivotally mounted for rocking movement and having a crossbar over which the web of paper feeds from the supply roll to the platen roll, a second bail pivotally mounted on the first bail and having a crossbar adjacent the crossbar of the first bail to grip the paper therebetween, spring means connected to rock the bails in the direction opposite the direction in which the web feeds from the supply reel, said second bail having an extending arm, and a stop engaged by the extending arm of the second bail to cause the bails to rock relative to each other at a predetermined time during the rocking movement of the first bail to release the paper web therebetween to permit the feeding of an increment of paper from the supply reel between the bails.
